Fig. 4.

Fig. 5.

Fig. 6.

Fig. 7.

FIG. 1 is a perspective view for a casing for hand held hair dryer embodying my new design;

FIG. 2 is a top plan view thereof;

FIG. 3 is a side elevational view of the side opposite that shown in FIG. 1;

FIG. 4 is a bottom plan view thereof;

FIG. 5 is a front elevational view thereof;

FIG. 6 is a rear elevational view thereof; and

FIG. 7 is a cross sectional view taken along line 7—7 of FIG. 3;

I claim:

The ornamental design for a casing for hand held hair dryer, as shown.
